HYDRAULIC SYSTEM, INCLUDING MULTIPLE MOTORS AND CONTROLS THEREFOR

Bartholomew F. Quintilian, Baltimore, Md., assignor to Gerotor May Corporation, a corporation of Maryland

Application July 15, 1947, Serial No. 761,052

3 Claims. (Cl. 60—53)

1

My invention relates to control systems, and more especially to fluid motor systems and motor control valves.

Among the objects of my invention is the provision of a simple, reliable and highly practical hydraulic multiple motor control system in which fluid is reliably and effectively distributed to appropriate motors in accordance with power demands encountered, and which system is efficient in the appropriate stages of motor operation for meeting the power demands.

Other objects in part will be obvious and in part pointed out hereinafter.

The invention accordingly consists in the combination of elements, features of construction and arrangement of parts and in the several steps and the relation of each of the same to one or more of the others as described herein, the scope of the application of which is indicated in the claims.

In the several figures of the accompanying drawing, provided for representing an illustrative embodiment of my invention, Figure 1 schematically indicates a dual hydraulic motor control system, and Figure 2 is a longitudinal section of a motor control valve employed in the system.

Like reference characters denote like parts in the two views.

As conducive to a clearer understanding of certain features of my invention, it may be noted at this point that rotary hydraulic motors are coming more and more into demand for operation against loads which vary through a considerable range. In these instances, a proper capacity of the motor in view of expected power demand becomes important to actual fulfillment of functions and the achievement of overall satisfaction and efficiency of operation of the system throughout the expected load range. It often becomes impossible, however, to enjoy reliable and efficient operation in wide ranges with a single motor, as where the motor is too small for developing a sufficiently high torque yet is capable of operation at high speed under reduced load. On occasions this is accompanied by stalling; stoppages and breakdown of the hydraulic motor or the related parts of the system.

In dealing with the problems of operating a single motor, therefore, it sometimes becomes desirable to cut in, operate, and cut out additional motor units to meet the varying loads, and in the event of excessive load, to relieve all power units, and stop overall operation. A number of the multiple motor hydraulic systems heretofore provided for selective motor operation, however, are

extremely complicated in view of functions to be achieved and are difficult to install and maintain. In others of these systems the selective distribution of fluid is not well suited for supplying energizing fluid to hydraulic motors which operate against a varying load.

An outstanding object of my invention accordingly is the provision of a simple, practical and reliable multiple hydraulic motor system enabling highly satisfactory valve control over the motors therein for meeting varying power demands, and which system is easy to install and maintain in efficient operating condition.

Referring now more particularly to the practice of my invention, I provide a multiple motor hydraulic system in which at least one of the motors is supplemented in its driving action by one or more aiding motors or left to operate alone depending upon the load encountered. This system advantageously includes a high speed low torque motor 10 (see Figure 1) of the rotary hydraulic type which alone has a sufficient capacity to accommodate power demands while subjected to a relatively small load, and a high torque, low speed hydraulic motor 11, also of the rotary type, is hydraulically and mechanically connected in aiding relation with the first motor to contribute power as occasions may arise in view of the load. For the sake of contributing to such features as compactness, directness and simplicity of the system, the two motors preferably have their rotors mounted on a single power output shaft 13 for driving against load. These two motors sometimes are housed within the same casing and for all intent and purposes amount to a single unit having two available stages for operation.

The low torque motor 10 conveniently is in an uncontrolled hydraulic circuit with a fluid pump 12, as for example a constant delivery rotary pump suited for pumping a constant quantity of energizing fluid such as oil or water. This uncontrolled circuit illustratively includes fluid supply conduit 14 interconnecting the output side of the pump with the intake side of the motor, conduit 15 leading from the motor outlet to a storage reservoir 16, and conduit 18 for admitting fluid from the reservoir to the pump.

The high torque hydraulic motor 11 is in parallel hydraulic circuit with the motor 10. A control valve 20 disposed in the parallel branch circuit including the aiding motor serves to control the distribution of fluid in the overall system, in a manner which will be more fully explained hereinafter.

My control valve illustratively comprises a casting having an inlet port 21 at one end thereof

emptying into a fluid receiving chamber 22, and longitudinally spaced outlet ports 25 and 26 extending through the casing sidewall from the chamber. All of these ports are advantageously controlled by a piston 23 received in the casing through opening 28. The piston is guided for reciprocative movement to and from the inlet port by a suitable slide-bearing (not shown) in the wall of the casing at the opening just noted. The piston has an enlarged end or head including tapered portion 23a which seats against the wall of the casing around the inlet opening for closing off this opening from communication with both of the outlet ports. The fluid receiving chamber 22 preferably is sufficiently large to define a space with the piston for communication between the two outlet ports when the inlet port is closed as just described. In full retracted position, the piston head enters a reduced bore section 22a of the fluid receiving chamber 22. A cylindrical portion 23b of the enlarged end or head of the piston there serves to close off the outlet port 25 while leaving inlet port open to outlet port 26. In intermediate positions of the enlarged piston end, between the opposite ends of chamber 22, the inlet port conveniently is open to both outlet ports.

The control valve 20 preferably includes a pressure relief valve 30 as a unitary part thereof for relieving fluid pressure in excess of a certain amount. I usually build this relief valve into the control piston 23. Where this is done the piston illustratively has an orifice 30a in the tapered end portion 23a thereof, an enlarged axial bore 30b for receiving fluid through the orifice, and a ball check 30c normally seating over the orifice from within the bore. A coil spring 30d compressed in the bore 30b between the ball and the innermost end of the bore serves to maintain closure of the orifice up to a certain counteracting fluid pressure. The relief valve also has an outlet port 30e which empties into chamber 22 of the control valve and into outlet port 25 as will be more fully explained hereinafter.

With particular reference again to the embodiment of my multiple motor hydraulic control system represented in Figure 1, it will be seen that the aiding parallel branch circuit includes fluid pump 12, conduit 14 to junction 47, fluid line 48 leading from this junction to inlet 21 of the motor control valve 20, conduit 19 interconnecting outlet 26 of the control valve and inlet side of the aiding motor 11, fluid exhaust lines 42 and 44 extending from the motor outlet to the junction 21, conduit 15 to the reservoir 16, and conduit 18 back to the pump. A line 45 for bypassing fluid around both of the hydraulic motors 10 and 11 leads from outlet 25 of the control valve to junction 43 with exhaust line 44.

With the piston 23 of the control valve set to the position indicated in Figure 1 of the drawing, the inlet port 21 of the valve is closed. The hydraulic pump 12 during operation then draws fluid from the reservoir 16 and supplies this fluid through conduit 14 to the motor 10. A rotation thus is imparted to the rotor of this motor and the related shaft 13. Fluid exhausts from the motor through conduit 15 back to the reservoir. The fluid pressure developed during this time on the inlet side of the motor is transmitted through line 48 to the closed inlet port 21 of the control valve. Should the pressure become excessive, such as by attaining a value beyond desired limits of operation of the system, the relief valve 30 is opened, ball check 30c lifting and thus admitting fluid through orifice 30a, bore 30b, outlet

port 30e and chamber 22. A substantial quantity of this fluid then escapes through outlet port 25, bypass line 45 and exhaust line 44, to conduit 15 at junction 21, and through conduit 15 back to the reservoir 16, thus circumventing the motor 10. This escape continues until certain operating pressures in the system are resumed, at which time the relief valve 30 again closes and is held closed by the coil spring 30d acting on ball check 30c.

When the motor 10 alone is exposed to the energizing effect of fluid supplied from the pump 12, in the manner described, shaft 13 serves to rotate the rotor of motor 11. The idling motor 11 therefore tends to function as a pump to the extent of its displacement. Thus, to avoid the development of a vacuum as on the valve 20 in view of this pumping action, I rely upon a fluid recirculation circuit, including the motor 11, the motor exhaust line 44, line 45, outlet port 25 of the control valve, chamber 22, outlet port 26, and conduit 19 leading back to the motor. Fluid pumped by the motor, accordingly, passes at low pressure through this circuit without impairment or injury to the system. At times, I find advantage in employing an over-running clutch 50 between the shaft 13 and the rotor of motor 11 for disconnecting the shaft and rotor when the motor 10 alone is operating.

By displacing the piston 23 of the control valve to a position such as represented in Figure 2, thereby closing the outlet port 25 and putting the inlet port 21 and outlet port 26 in open communication, the aiding motor 11 comes into operation, this while the motor 10 continues operation. Where the pump 12 is a constant delivery pump, the same quantity of fluid continues to come into the system as compared with that in single motor operation. Fluid for producing the aiding motor function is pumped from the reservoir 16 through conduit 18 by the pump 12 and then is supplied through conduit 14 to junction 47, thence through fluid line 48, inlet port 21 of the control valve, fluid receiving chamber 22 of this valve, outlet port 26, through conduit 19 and the aiding motor 11, fluid exhaust line 42 to junction 43, exhaust line 44 to junction 21, and thence through conduit 15 back to the reservoir. In the instance of high-torque low-speed operation of the motor 11, the driven shaft 13 receives the additional torque, which serves to supplement the output of the motor 10. Should pressure in the system exceed the seating pressure of the coil spring 30d on the ball check 30c, this pressure is relieved by the relief valve 30. The relief is effected by fluid passing through orifice 30a, bore 30b and outlet port 30e, and to outlet port 25 in the control valve casing. The fluid then exhausts through lines 45, 44 and 15, respectively, back to the reservoir 16, thus bypassing both motors. This bypassing action maintains until a sufficiently low pressure is resumed in the system, at which time the relief valve 30 closes. Both motors continue their coupled driving effect on the shaft 13 until the piston 23 is reset to close the inlet port 21 as for resuming high-speed low-torque operation of the motor 10.

The high and low speed motor control positions of the piston 23 of the control valve 20 are conveniently achieved with the aid of suitable manual setting means, or by suitable automatic means for giving a setting of the piston consistent with the motor load. In positions of the piston between those giving single motor operation and multiple motor operation, fluid admitted through inlet opening 21 to chamber 22 and outlet open-

ing 25, causes a sufficient drop in pressure in the entire hydraulic system for stopping either or both motors.

Thus it will be seen that in this invention there are provided a multiple motor control system and control valve in which the various objects noted herein together with many thoroughly practical advantages are successfully achieved. It will be seen that the system is well suited for operating under load and for achieving single or multiple motor operation consistent with varying power demands. It will be observed also that the control valve is simple, compact and capable of giving highly satisfactory control over a plurality of fluid motors and enables the selective operation of one of these motors to the exclusion of another.

As many possible embodiments may be made of my invention and as many changes may be made in the embodiment hereinbefore set forth, it will be understood that all matter described and illustrated herein is to be interpreted as illustrative and not as a limitation.

I claim:

1. A multiple motor control system, comprising in combination, a source of pressure fluid supply including a reservoir, at least two fluid motors connected in aiding mechanical relation with each other, a fluid circuit directly connecting one of said motors with said source of supply, a parallel fluid circuit connecting another of said motors with said source of supply, and a fluid control valve having a chamber with an inlet and two outlets connected in said parallel circuit, one outlet leading to said other motor and the other outlet leading to said reservoir, said valve having movable piston means in said chamber for selectively sealing off said inlet port in one position thereof and said other outlet port in another position and while in the inlet port closing position admitting intercommunication of said outlet ports, said piston means including an axial bore with spring seating valve means forming a pressure relief valve for spilling off fluid through the other one of said control valve outlets for said two fluid motors when the piston means is in either of the selected positions.

2. A fluid control valve comprising in combination, a casing having a fluid receiving chamber and an inlet port and a plurality of outlet ports for the chamber, and a fluid control piston in said chamber for selectively sealing off said inlet port in one position thereof and one of said outlet

ports in another position, and while in the inlet port closing position admitting intercommunication of said outlet ports, said piston including an axial bore with orifice therein in continual communication with said inlet port, a ball check received in said axial bore, a spring also received in said bore and maintaining said ball to close said orifice, and an outlet from said bore to effect pressure-responsive relief for said valve in either of the selected piston positions.

3. A fluid control valve comprising in combination, a casing having a fluid receiving chamber and an inlet port and a plurality of outlet ports therein for the chamber, and a fluid control piston in said chamber for selectively sealing off said inlet port in one position thereof and one of said outlet ports in another position, and while in the inlet closing position forming a space with said casing wall communicating with said outlet ports, said fluid control piston including an axial bore with spring seating valve means therein for relieving fluid exceeding a predetermined pressure value in either of the selected positions of the piston and having an outlet emptying from said axial bore into the selective outlet port in the casing.
